UNITED STATES PATENT OFFICE.

JOHN E. WATSON, OF LOUISVILLE, KENTUCKY, ASSIGNOR TO THE INTERNATIONAL ELECTRICAL COMPANY, OF SAME PLACE.

METHOD OF OPERATING WITH ELECTRICAL CONDUCTORS.

SPECIFICATION forming part of Letters Patent No. 371,531, dated October 11, 1887.

Application filed April 11, 1887. Serial No. 234,372. (No model.) Patented in Belgium April 12, 1887, No. 77,046; in Spain May 26, 1887, Nos. 10,814 and 1,397, and in Italy June 30, 1887, Nos. 21,589 and 439.

To all whom it may concern:

Be it known that I, JOHN EDWARD WATSON, a citizen of the United States, resident at Louisville, in the county of Jefferson and State of Kentucky, have invented certain new and useful Improvements in Methods of Operating with Electrical Conductors, (for which I have obtained Letters Patent No. 77,046, dated April 12, 1887, in Belgium; Letters Patent No. 21,589 and No. 439, dated June 30, 1887, in Italy, and Letters Patent No. 10,814 and No. 1,397, dated May 26, 1887, in Spain;) and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a diagrammatic representation illustrating the method or process. Fig. 2 is also a diagram illustrating the process and indicating the circuits for the near and distant stations.

This invention has relation to an improvement upon the present methods of communicating or signaling by electricity, and it is designed to involve not only those arts—such as telegraphy—in which the received signals are apparent to the eye and ear, but also those in which the signals are appreciable through sound alone. And while the more important purposes of the invention refer to the facilitation of electrical communication over lines of great length and resistance, it will be found to offer material advantages when applied to short lines or circuits. The method is readily applicable to all or nearly all modes of signaling in use, whether the Morse system, the printing method, the chemical recording, or the autographic be employed. It will also be found serviceable in systems of automatic electric signaling, in the distribution of time signals, &c., over lines of great length, and wherever it may be necessary or advisable to operate with weak or feeble currents its advantages will be apparent.

It is well known that the magnetism or magnetic force of translation, while strong near the pole or poles of a magnet or electro-magnet, is at a distance from such pole or poles very fee-

ble or weak; and the object of this invention is to utilize this feeble or weak influence, which is far less variable between two points at a certain distance from each other in its direction of action than is the strong force near the pole between two points situated the same distance apart, or even nearer to each other. This distant influence I shall call, for the purposes of this description, the "poising-force," and its scope, or the limits within which it can be made available, the "poising-field." This field is practically outside the limit of residual magnetism. In carrying out this method of electrical signaling, apparatus is necessary according to the line of application, whether it be employed in facilitating telegraphic or telephonic communication, galvanometry, the electric regulation of time-keepers, or any form of electric signaling or recording wherein rapidity, certainty, and delicacy of action are required, and it may readily be illustrated in its adaptation to facilitate electrical communication over conductors, as inland and marine telegraphy. To this end I employ, in addition to the main line or conductor, its battery, and key or transmitter, a relay having a local circuit and battery and a sounder or indicator; or the relay may itself serve as the indicator, recorder, or receiving-instrument, for it is designed, in the utilization of the features of this invention, to effect, among other objects, simplification of apparatus.

In the diagram, the letter L designates the main line or conductor, and B the main-line battery.

C is the key or transmitter, and D the relay, having an electro-magnet, E, and armature F, the latter being in or a part of the sounder or indicator circuit U.

H is the local circuit of the relay, having its battery K, and the relay-magnet is wound not only in the local circuit H, but also in the main-line circuit, in such a manner, however, that the local current runs in the opposite direction to that of the main line. With this object in view, the relay-magnet may be directly wound in the local circuit and reversely wound in the main line. But it is, however, preferred to wind the helices directly in both circuits and to run the currents therein in opposite directions. In this magnet the helix

or helices of the main line are formed of many turns of fine wire, as indicated at *m*, while the helix or helices of the local circuit are formed of comparatively few turns of coarse wire, or 5 wire of comparatively low resistance, as indicated at *l*. The coarse wire is usually wound next the axis or core and the fine wire over the coarse wire; but the arrangement may be reversed, the coarse wire being wound to 10 form the outer layers. In either event, however, the coarse-wire helix, or helix of low resistance, is in communication with the poles of the local battery, and the fine wire, or helix of high resistance, is in connection with 15 the main line. These helices are properly insulated from each other by winding the wires with silk or other insulation in the customary manner.

F is the armature of the relay, which may 20 be pivoted, hung, or otherwise arranged to have a movement in front of the pole or poles of the electro-magnet.

N is a rest-stop, and *P* a contact-stop, the latter being in the sounder or indicator circuit 25 *U*, and so arranged that when contact is made between the armature and the stop *P* the sounder or indicator circuit is closed. In some apparatus, and especially in telephonic receivers, wherein the armature is a diaphragm, the 30 armature itself is the sounder or indicator.

S represents a spring, weight, or other tension of the armature. Its own gravity will serve the purpose, if the armature and magnet are in suitably relative positions. In the case 35 of a telephonic receiver the tension of the diaphragm is sufficient.

The method of operation is as follows: The local circuit being always closed, the magnetism thereof, acting through the low-resistance 40 helices of the relay upon its armature, which is located not so near the magnetic poles as to be within the limit of the strong and quickly-varying influence thereof, but at a comparative distance therefrom within the poising-field 45 of magnetism, serves to counterbalance or poise the armature, or hold the same in a position of equilibrium. In the diagram, a counterbalance spring or tension is indicated at *S*; but, as I have hereinbefore explained, 50 this purpose may be served by the gravity of the armature itself or its inherent elasticity. The poising distance will vary with the size of the wire forming the low-resistance coils on the magnet and the strength of the 55 current of the local circuit, and may extend to one-eighth of an inch of the magnetic pole, and even closer. Or it may be found at a considerable distance therefrom. The armature may readily be brought to the position of 60 equilibrium when within the poising-field, the main line being open, by adjusting the magnet or the tension, or by introducing resistance in the local circuit or by adjusting the armature itself. The main circuit being closed the contact and rest stops, when these are employed, 65 are adjusted by suitable adjusting devices, as indicated at *I* and *J*, in proper position, and

the receiver is ready for communication. In the diagram the armature is shown in contact with the platinum-stop *P* of the sounder-circuit. Now, it will be explained that when the main-line current is operating in the fine-wire or high-resistance helix of the relay its action is opposed to that of the coarse-wire or low-resistance helix of said relay, and its effect is to neutralize to a certain extent the magnetizing influence of said low-resistance helix, thereby weakening the attractive power (or force of translation) of the electro-magnet and allowing the armature to move back to position of contact under the action of its spring or tension, closing the local sounder or indicator circuit. In transmitting, the sending-key or transmitter is opened, interrupting the flow of the main-line current in the high-resistance helix and allowing the helix of the local circuit or low-resistance helix to regain at once its full magnetizing power, whereby the armature is drawn forward to its position of equilibrium, or against the rubber stop *N*. 90 When the key is closed to make a signal, the main current, passing in the fine-wire helix, at once destroys the equilibrium of the armature, and it is thrown back by its weight or tension to contact position, closing the local sounder 95 or indicator-circuit. When, however, the key is opened or raised to break circuit in the main line, the full magnetism of the electro-magnet promptly asserts itself, drawing the armature from the contact-stop and breaking the local-sounder circuit. And it should be further explained that, in the case of a telephonic receiver, when the diaphragm is the armature and sounder and there are no contact and rest stops, the state of counterpoise or equilibrium 100 of the diaphragm involves the opposition of its own tension on the one hand and of the distance or poising magnetic force on the other. For if the diaphragm be adjusted near the pole, or within the strong and quickly-varying 110 field of magnetism, the tension of said diaphragm would be so powerful that the hampering influence of the feeble current of the main line in the electro-magnet would be insufficient to appreciably lessen the magnetic 115 attraction thereon.

In this method it is designed to avoid nearly, if not completely, all retarding and inductive troubles of the main line. Even should such be present, and of sufficient electro-motive 120 force to affect the fine-wire helix, there would be no appreciable evil effect therefrom in the coarse-wire helix, which is the chief magnetic element of the relay or receiver.

In this method of operating it is designed 125 to locate the armature in the poising-field of magnetism, which is at such a distance from the poles that the effect of residual magnetism is reduced to a minimum, and may practically be disregarded. In all the modes heretofore 130 in use the armature has been worked in the strong field of residual magnetism, where all the evils of induction have had full sway.

In winding the helices of the electro-magnet

much latitude is allowable. I have obtained excellent results when using for the high-resistance helices some eighteen thousand turns of No. 37 wire of Birmingham wire-gage, and for the low resistance about two hundred and fifty turns of No. 26 wire, same gage. A local battery of from one to two volts will serve an excellent purpose. Of course if the battery is stronger in proportion to the resistance of the low-resistance coils the point of equilibrium of the armature will be farther from the poles of the electro-magnet for the same degree of tension and the instrument will be more delicate. Very little magnetic force is required to move the armature when arranged at a distance from the poles in the manner specified. If the local battery is stronger, the distance of the armature from the poles must be increased to obtain equilibrium. While a battery of double strength will not require that the armature be set at double distance, yet the distance will be greater and the delicacy of the equipoise will be increased many times.

For railway-signaling the invention will be found to possess superior advantages, because it is designed that the apparatus involved shall not be liable to serious disturbance on account of rain or dampness. In the practical operation of this method it will be apparent that it is intended to use currents of exceeding weakness, or of such low order that no casual conduction, set up by atmospheric conditions or otherwise, can deflect them from their proper paths. In fact, it is believed that by this mode of telegraphy railway-rails, fence-wires, and other extending metallic lines, originally intended for other and different purposes, can, with some modifications of connection, be utilized as conductors of the weak currents which I employ; for it should be borne in mind that the principle of this invention involves the use of a weak current of electricity to oppose and limit the magnetizing influence of a closed local circuit, and thereby hamper the magnetism, acting upon an armature at a distance from the magnetic pole, in contradistinction to the employment of a strong current of electricity to produce at a distance a magnet which will attract an armature when placed close to the poles.

Having described this invention, what I claim, and desire to secure by Letters Patent, is—

1. The method or process of telegraphy or electric signaling, which consists in, first, bringing to a position of equilibrium a mechanically-counterpoised armature of an electro-magnet, involving a constantly-acting direct local current, and a second reversely-acting current in the main line, passing in coils of low and high resistance, respectively, on a common soft iron-core, and, secondly, operating said armature by said local current for its attraction, and to make signal by a tension exterior to the circuits, but conditioned upon the

action of the main-line current for its retraction, substantially as specified.

2. A system of electric signaling consisting of a local circuit including a magnet with low-resistance coils, and an armature poised by the attraction of the magnet and an opposed tension, and a main-line circuit including high-resistance coils superposed on the core of the aforesaid magnet, and passing the current reversely to that in the local circuit, whereby a current in the main line too weak to cause an attraction of the aforesaid armature will lessen the attraction of the magnet in said local circuit, and thus cause the tensile force to preponderate, substantially as specified.

3. In a system of electric signaling, the method of producing motion of the armature of an electro-magnet counterpoised at a distance from its poles, between the electro-magnetic attraction set up by the coils of low resistance on the core of said electro-magnet on the one hand and the tension of the armature on the other hand, by passing a weak main-line current through high-resistance coils on the same core in the reverse direction to that of the current passing in the coils of low resistance to lessen the magnetic attraction in response to action in the main line, and ceasing the action of said main line to allow the electro-magnet to regain its maximum power of attraction, substantially as specified.

4. In an electro-magnetic relay, the combination, with a magnet involving a constantly-acting direct current in local circuit, and a second reversely-acting current in the main line, passing, respectively, in coils of low and high resistance on a common soft-iron core, of a poised armature in the indicator-circuit and its tension opposing the attractive power of the magnet to effect the counterpoise of said armature, whereby a current in the main line too weak to cause attraction of the armature will lessen the attraction of the magnet in the local circuit and cause the tensile force to preponderate to retract the armature to close the indicator-circuit, substantially as specified.

5. A relay electro-magnet having an armature counterpoised by its tension opposing the electro-magnetic attraction, and having on its core coils of low resistance involved in a constantly-closed direct local circuit energizing the same, and coils of high resistance, separate and insulated from the low-resistance coils, energized by a main current acting in the reverse direction in said coils to lessen the magnetizing effect of the low-resistance coils and allow the tensile force to preponderate and to retract the armature, substantially as specified.

In testimony whereof I affix my signature in presence of two witnesses.

Correction in Letters Patent No. 371,531

It is hereby certified that the name of the assignee in Letters Patent No. 371,531, granted October 11, 1887, upon the application of John E. Watson, of Louisville, Kentucky, for an improvement in the "Method of Operating with Electrical Conductors," was erroneously written and printed "The International Electrical Company," of same place; that said name should have been written and printed *The International Electric Company*, of same place; and that said Letters Patent should be read with this correction therein that the same may conform to the record of the case in the Patent Office.

Signed, countersigned, and sealed this 25th day of October, A. D. 1887.

[SEAL.]

D. L. HAWKINS,
Acting Secretary of the Interior.
